Attorney

UNITED STATES PATENT OFFICE.

THOMAS L. YOUNG, OF SEATTLE, WASHINGTON.

SANITARY TOILET-SEAT COVER.

Application filed August 17, 1926. Serial No. 129,819.

This invention relates to a sanitary seat cover for toilets, comprising a sheet of destructible material made to conform to the seat and having flaps designed to facilitate the carrying away of the cover after use.

The principal object of the invention is to provide a seat cover of this character having flaps designed to hang into the interior of the bowl to facilitate the carrying away of the cover in the flushing operation.

The invention is illustrated in the accompanying drawings, in which:

Fig. 1 is a plan view of the seat cover.

Fig. 2 is a side elevation of the same.

In the drawings, 1 indicates the main body of the seat cover, which is rectangular in outline, having a partly cut flap 2, the line of cut 3 following the outline of the seat proper. The flap is connected as at 4 and 5 to the main body of the cover, the length of connection at 4 at the rear of the flap being considerably greater than the length of connection at 5, the latter being at the front of the flap and disposed opposite to the connection 4.

A second flap 6 hingedly connected at 7 to the flap 2 and otherwise free of connection with the flap 2, is arranged to act in cooperation with the flap 2 in providing a resistance to the flushing water, to thereby more positively insure that the seat cover will be carried away.

In use, the main body 1 is applied to the toilet seat, the flap 2 is detached along the connection 5 and allowed to drop down into the interior of the bowl, being still connected to the body portion 1 through the connection 4. It will be noted that connection 5 is of less extent than connection 4, and therefore upon

application of pressure to the flap 2, the connection 5 will be ruptured without correspondingly separating the flap at connection 4. On the dropping of flap 2 into the interior of the bowl, the flap 6, being connected to the flap 2 only at 7, arranges itself so that its plane is at an angle to the plane of flap 2, thus providing flaps set at two different angles to offer resistance to the movement of the flushing water. In flushing, the water striking the flaps will draw the main body 1 down into the bowl, thus insuring the carrying away of the used seat cover.

The seat cover being made of the usual flimsy material is therefore cheap to manufacture, and with the provision of the double flaps as described, the removal of the sanitary seat cover is thereby insured.

What I claim as new is:

In a sanitary commode seat cover of the class described, a thin piece of pliable material adaptable to cover the seat, a flap in the center of the said material of a somewhat smaller size than the opening of the seat, said flap being separated from the piece of material along the sides, temporarily attached at one end and permanently attached at the other; and a second flap within the said former flap and attached to it at one end only, the end at which the secondary flap is attached being opposite to that at which the larger flap is permanently attached so that as the flaps drop into the bowl the secondary flap will extend beyond the free end of the larger flap to insure its being caught and removed by the flushing water.

In testimony whereof I affix my signature.

THOMAS L. YOUNG.
